United States Patent Office

Des. 196,862
Patented Nov. 12, 1963

196,862

PLATE OR SIMILAR ARTICLE

Shigeru Masuda, Nagoya, Aichi, Japan, assignor to
Noritake Co., Inc., New York, N.Y., a corporation of
New York

Filed July 30, 1962, Ser. No. 71,097

Term of patent 3½ years

(Cl. D44—15)

FIG. 1

FIG. 2

FIG. 1 is a top plan view of a plate or similar article showing my new design, only a portion of the design being shown between dotted lines; and

FIG. 2 is a view to enlarged scale of a portion of the design shown in FIG. 1, a repeat segment being shown between dot-and-dash lines.

The plate is of a conventional configuration when viewed from the side and bottom thereof.

I claim:

The ornamental design for a plate or similar article, substantially as shown and described.
